UNITED STATES PATENT OFFICE.

FRANK J. CASE, OF ARRINGTON, KANSAS, ASSIGNOR OF TWO-THIRDS TO
F. L. & H. J. CASE, OF SAME PLACE.

BROOM.

SPECIFICATION forming part of Letters Patent No. 404,258, dated May 28, 1889.

Application filed July 10, 1888. Serial No. 279,511. (No model.)

To all whom it may concern:

Be it known that I, FRANK J. CASE, a citizen of the United States, residing at Arrington, in the county of Atchison and State of Kansas, have invented new and useful Improvements in Whisks and Brooms, of which the following is a specification.

The invention relates to improvements in whisks and brooms; and it consists in the construction and novel combination of parts, hereinafter described, illustrated in the accompanying drawings, and pointed out in the appended claims.

In the drawings, Figure 1 represents a view of one side of a broom, illustrating the invention. Fig. 2 represents an edge view of the same. Fig. 3 represents one side of the broom with the plate metal removed. Fig. 4 is a central vertical section of the same. Fig. 5 represents a perspective view of one of the retaining-bars for the straw. Fig. 6 is a horizontal section through the clamping-bars.

Referring to the drawings by letter, A indicates a broom-handle, and B the broom, which is not directly connected or wired to the handle.

C C are similar opposite sections of sheet-metal casing, forming, when closed together, the shoulders of the broom. 30 c c are laterally-curved strips projecting from the sheet-metal sections upon the broom-handle, each being provided with the scalloped edges c', running upward to a point. The said strips fit upon and are attached by tacks or otherwise to opposite sides of the broom-handle.

D is a metallic sleeve slipped down on the handle over the strips c, where it is properly secured and prevents the said strips from 40 coming loose. The metal plates C are rounded or curved, and are provided with flanges E E on their shoulders and side edges, and have near their lower edges the transverse curved grooves F F, running from one side of said 45 plates and forming raised portions or beads on the outside thereof. The said raised por-

tions are parallel to the lower edges of said plates, and have their convexities downward.

G G are curved bars lying in the grooves or recesses F and having their end portions, f, 50 bent at right angles in order to lie against the edges of the bundle of broom-straw B, inserted between the plates and the bars G. The end portions, f, are beveled, so that the end portions of one strip will lie upon the corresponding end portion of the other strip.

When the broom-straw, handle, plates, and retaining-bars are all in place, rivets or bolts H are passed through registering-openings in the said plates and bars, and said rivets are 60 upset or headed on the outer sides thereof. When the bolts are used, their threaded ends are engaged by nuts h. It is preferable to use the bolts and nuts, as then the parts could be easily taken apart to renew the broom-straw should the same become worn, broken, or dirty. The broom-straw has its inner ends 65 free and abutting against the shoulders of the metallic side plates.

Having described my invention, I claim— 70

1. In a broom, the handle, the two similar metal plates, C, connected to the handle by the projecting strips c, and having the side flanges, E, and the curved bars G on the inner side of the plates, and the bolts passed 75 through the plates and also through the bars, as set forth.

2. In a broom, the combination of the handle, the bundle of broom-straw unconnected to the handle, the metal plates C, provided 80 with the projecting strips c, the flanges E, and the transverse grooves F, and the curved bars G, lying in said grooves and connected through the straw to the metal plates and to each other, substantially as specified. 85

In testimony that I claim the foregoing as my own I have hereto affixed my signature in presence of two witnesses.

FRANK J. CASE.
